US00D486202S

(12) **United States Design Patent** (10) Patent No.: **US D486,202 S**
 Rae et al. (45) Date of Patent: ** Feb. 3, 2004

(54) **KNIFE**

(76) Inventors: **Kit Rae**, 2841 Yarberry Edge La., Kodak, TN (US) 37764; **Calvin Brook Boling**, 20420 River Bend Loop, Apt. #1, Pigeon Forge, TN (US) 37863

(**) Term: **14 Years**

(21) Appl. No.: **29/181,274**

(22) Filed: **May 7, 2003**

(51) LOC (7) Cl. **22-02**

(52) U.S. Cl. **D22/118**

(58) Field of Search **D22/118; 30/294, 30/295, 340, 342, 343-345; D7/649; D8/95, 98, 99**

(57) **CLAIM**

The ornamental design for a knife, as shown and described.

DESCRIPTION

FIG. 1 is a left side elevational view of the design of the present invention for a knife, of which the right side is a mirror image thereof;

FIG. 2 is a top plan view of the knife of FIG. 1;

FIG. 3 is a front elevational view of the knife of FIG. 1;

FIG. 4 is a rear elevational view of the knife of FIG. 1; and,

FIG. 5 is a bottom plan view of the knife of FIG. 1.

1 Claim, 4 Drawing Sheets
